PROTECTIVE COLLAR UNIT FOR REFRIGERATING COILS

George Seiler, Chicago, Ill.

Application April 26, 1945, Serial No. 590,458

6 Claims. (Cl. 62—147)

1

My invention relates to a new and useful manufacture, i. e., a protective collar and overflow bracket, made of cast iron or other suitable material, for use in connection with spiral cooler coil such as are commonly used by taverns for cooling liquids or beverages and which make use of ice or mechanical refrigeration.

In apparatus for cooling beverages, it is common practice to provide standard cylindrically sleeved coil cooling units which furnish no protection to the spiral coil pipe from injury in the process of poking and packing ice into the surrounding ice chamber, as a result of which practice the coil pipe will in time expand and stretch upwardly because of pressure due to manual packing of ice and work up and over the top rim of the cylindrical sleeve and will otherwise be distorted, displaced or damaged.

The present invention remedies this objectionable condition by the provision of a flanged protective collar unit that will prevent the coil from slipping up within the cooling chamber and will prevent its lower portions from being damaged in the course of manually packing ice down into the surrounding ice chest or chamber.

The objects of my invention are—

(1) By means of the protective, flanged collar securely, though adjustably, set into and over the top or rim of cylindrical sleeve of the standard types of coil refrigeration units common to liquid dispensing apparatus, to prevent damage and distortion to the coil pipe when filling the tank with ice and when packing ice into the ice chest or icing chamber.

(2) By means of a bracket adjustably attached to the wall of cooling chamber, or, in the alternative attached to faucet shank, and slipped into and through an oblong slot of an integral extension of the protective collar, to maintain the cylindrical sleeve and spiral coil unit in upright proper position and the mounting bracket thereof of above overflow level.

(3) By means of a rubber bushing set into a small round aperture and seat of an integral extension of the collar, to hold rigid and solid, and keep from distortion and displacement, the upper coil pipe sections leading into and connecting with the dispensing faucet.

With the above mentioned and other objects in view, my invention consists in the novelty of its concept, and in its simplicity of construction and of installation. Other and further objects and advantages of my invention, its arrangement and combination of parts, will appear from the following description, taken in connection with

2

the accompanying drawing, and particularly pointed out in the appended claims.

Referring now to the drawing:

Fig. 1 is a longitudinal section of my invention showing a position of protective collar over and flanged into the top of coil pipe cylindrical sleeve unit of standard refrigeration or beverage cooling systems.

Fig. 2 is a bottom plan view of my invention, viewed on line 2—2 of Fig. 1.

Fig. 3 is a detail cross sectional view of flanged collar and bracket, viewed on line 3—3 of Fig. 1, showing one form of bracket for attachment to an ice chest or wall of an icing chamber, and also showing the position of the bracket above slot and above the normal overflow level.

Fig. 4 is an elevational view of my invention with a modified type of mounting bracket showing an enlarged aperture or orifice for connection of the shank of dispensing faucet.

Fig. 5 is a detail cross section of said bracket, viewed on line 5—5 of Fig. 4.

Fig. 6 is a longitudinal section of my invention showing alternative means of connecting said mounting bracket to the faucet shank, and showing a rubber bushing mounted on the top end of the coil leading to dispensing faucet.

Similar characters refer to similar parts in the several figures of the drawing.

Referring to Fig. 1, reference character 11 designates the top-side or upper flange of the protective collar with integral flange 12 extending downward from inner perimeter of said collar, which collar is fitted into and over the top of cylindrical metal sleeve 24 of the spiral coil cooling unit 20. The upper bracket end 13, which is preferably integral, is connected to wall 19 of ice chest or box and the lower depending bracket section 14 is slidably mounted in position through slot 16 formed in inwardly extending ring member 17, which is integral with said collar unit. The coil terminal or end section 20 leading to faucet extends through aperture 15 of ring member 17 which, as stated, is integral with said collar unit and said coil end section is preferably held rigid within said aperture 15 by means of rubber bushing 18 set in the aperture of said ring extension 17.

Through orifices in said bracket as shown at 22 of Fig. 3 accommodate screw or other fastening elements 22 for secure attachment of the bracket to the wall of the icing chamber, as shown in Fig. 1.

In a modified form of mounting bracket illustrated in Figs. 4 and 6, reference numeral 13—b

designates a metal shank portion thereof which is equivalent to the apertured mounting portion described with reference to Figs. 1 and 3. Said mounting bracket portion 13—b is provided with a relatively large aperture or passage 13—a which is of sufficient size to be slipped and mounted upon the inwardly extending threaded nipple-like portion 25 of a conventional fitting 26 shown partially in cross section in Fig. 6. Said fitting 26 is mounted in the conventional manner in a suitable passage through the side wall of the ice chest and it is normally secured therein by a suitable lock nut 21 threaded on the inwardly extending nipple portion thereof. The inwardly extending portion 25 of the said fitting 26 terminates in a cone seat which is adapted to receive and be engaged by a suitable bushing 27 which is held in normally secured position by lock nut 28 as shown in cross section in Fig. 6. The said bushing 27 is securely mounted about the inwardly extending end or terminal section of the coil pipe 20 which is removably held in sealing engagement in said nipple portion 25 by said nut 28.

In the mounting of the adjustable bracket illustrated in Figs. 4 and 6, either on old or new coil box installations, it is only necessary to disconnect and withdraw the terminal section of the coil pipe 20 and remove the lock nut 21 and then mount the shank portion 13—b upon and about the nipple portion 25 and replace and tighten the lock nut 21 and reconnect the coil pipe section 20 by remounting the nut 28 to tightened position as illustrated in Fig. 6. The off-set or angular intermediate portion of said bracket maintains the depending lower portion 14 in a position sufficiently spaced from the ice box wall so as to provide ample space for the laterally extending flange 11 and guard 11 of the protective unit. As shown at 23 of Fig. 5, the backside of upper portion 13—b of faucet shank bracket is provided with two ribs running opposite and parallel to each other along the edge thereof to secure a tighter hold and to prevent distortion, as bracket backside is pressed against inner side of the ice box wall.

While the foregoing specification sets forth the invention in specific terms, it is to be understood that numerous changes in the shape, size and materials may be resorted to without departing from the spirit or scope of the invention as claimed hereinafter.

Having thus described the invention, what is claimed as new is:

1. A protective collar of substantially right angled cross section adapted to seat within and to cover the upper end section of a cooling coil, said collar having an integral inwardly extending projection provided with a slot-like aperture for the reception of the depending portion of a mounting bracket.

2. A protective metal collar having an integral inwardly extending projection provided with two

spaced apart apertures therein, one of said apertures being adapted to receive the lower end portion of a mounting bracket, and the other of said apertures being adapted to receive and hold in proper position a coil pipe terminal connecting with the liquid dispensing faucet.

3. A protective collar having an integral flange extending downwardly from the inner perimeter thereof; a curved laterally extending flange on said collar, and an integral inwardly extending projection having an elongated opening and having a second opening adjacent the innermost portion of said inwardly extending projection, said second opening being adapted to receive a coil pipe terminal section connecting with the dispensing faucet thereof, and a depending mounting bracket having a portion thereof extending through said elongated opening.

4. A protective collar made of hard material, having an integral flange extending downwardly from the inner perimeter thereof and having a slightly curved laterally extending flange, an integral inwardly extending projection on said collar and having a slotted opening, a mounting bracket having a depending portion slidably engaging said slotted opening, said projection having a second opening partially defined by a downwardly recessed seat, a rubber bushing mounted in said seat and adapted to frictionally engage and hold a coil pipe terminal section, said coil pipe section being connectable to a dispensing faucet.

5. A protective device adapted to hold and guard the upper portion of a spiral cooling coil and adapted to fit over and into a cylindrical sleeve within such coil comprising a passaged collar of angular cross section; a depending bracket having an upper apertured section adapted to be fastened to the refrigerated compartment wall at a point above the normal overflow level, said bracket having a depending arm extending through and engaging the passage of said collar.

6. In a device for protecting and holding the upper portions of substantially spiral cooling coils adapted to be contained within a refrigerating container, a protective collar of angular cross section having an inner downwardly depending flange and having a laterally extending flange adapted to overlie the upper end portions of said coil; a projecting member on said collar extending inwardly thereof and having a pair of spaced apart openings therethrough, one of said openings being adapted to receive the upper end section of the cooling coil; a metal bracket adapted to be secured in the upper part of a refrigerating container and having an integral downwardly extending arm normally extending and engaging the other of said passages in said inwardly extending member, said collar being movable along said bracket arm to permit mounting of said collar at varying positions.

GEORGE SEILER.
